NEIL MACLEAN CAMERON, OF SHOAL LAKE, MANITOBA, CANADA.

ATTACHMENT FOR BUNDLE CARRIERS.

1,419,542.

Specification of Letters Patent. Patented June 13, 1922.

Application filed April 26, 1920. Serial No. 376,778.

To all whom it may concern:

Be it known that I, NEIL MACLEAN CAMERON, of the town of Shoal Lake, in the Province of Manitoba, Canada, have invented certain new and useful Improvements in Attachments for Bundle Carriers, of which the following is a specification.

The invention relates to improvements in attachments for bundle carriers and the object of the invention is to provide an attachment on the customary form of binder bundle carrier which will positively prevent the sheaves discharged on to the bundle carrier from escaping prematurely over the ends of the bundle carrier teeth and will also allow of more sheaves being carried by the bundle carrier prior to discharging them, thereby making better rows of sheaves which not only facilitates in stooking operations but also in the loading of the sheaves.

A further object is to arrange the structure of the attachment so that it can be readily applied on existing types of binders and such that the whole device can be made in a cheap, strong, durable and reliable manner and entirely automatic in its action.

With the above objects in view the invention consists essentially in a plurality of sheaf retainers located at the outer extremities of selected teeth of the carrier and means for controlling the retainers to hold them positively against movement in the upright position during the interval that the carrier is being loaded and to drop them during the unloading movement of the carriers and to return them to their original upright position when the bundle carrier is returned to receiving position, the parts being arranged and constructed as herein-after more particularly described and later pointed out in the appended claims, reference being had to the accompanying drawing in which:

Fig. 1 is a perspective view of the bundle carrier fitted with my invention.

Fig. 2 is a plan view of a portion of the bundle carrier.

Fig. 3 is an enlarged sectional view through the bundle carrier shaft.

In the drawing like characters of reference indicate corresponding parts in the several figures.

I have not considered it necessary to enter into the details of the binder as the structure of the binder as well as the bundle

carrier is well known. Only those parts immediately associated with my invention are described and whilst these are shown and described in detail it will be readily understood that I do not wish to be limited to the precise construction shown as this varies in the various types of binders and my invention would be modified to comply with the existing conditions.

1 and 2 are a pair of stationary end brackets extending from the side of the binder and which are utilized to support the bundle carrier shaft 3 in the ordinary position. The shaft 3 carries a plurality of 60 similar normally horizontally extending teeth 4 which have their outer ends slightly up-turned as indicated at 5 and their inner ends bent upwardly and passing pivotally through the shaft and then bent down- 65 wardly as indicated at 6 and all connected swivelly to a connection bar 7. This bar is to the rear end in a lower plane than the shaft and the arrangement is such that by end shifting the bar the outer tips of the 70 teeth can be all swung simultaneously rearwardly and such that upon the shaft being 75 rotated the teeth can be thrown down towards or raised from the ground.

In the bundle carriers as at present used 80 and as shown these down swinging and rearward turning actions occur simultaneously, the teeth dropping and swinging rearwardly to effect the discharge of the bundles carried by the teeth in an easy and gradual 85 manner. The shaft and the bar are controlled in their movement by the means hereinafter described.

8 is a rotatably mounted operating rod 95 fitted with a downwardly extending crank 9, the lower end of which is connected by means of a pitman 10 to the bar 7. The shaft 3 is supplied with an upwardly extending crank 11 which is connected by means of a link 12 also with the crank 9. 100 Obviously the rotation of the rod 8 in a proper direction will shift the crank 9 rearwardly which action will produce two movements, to wit:—an end movement in the bar 7 and a rotary movement in the shaft 105 3 which movements are the ones which give the teeth the back turning and down dropping movement herein before mentioned.

All the above parts are of ordinary construction and do not form any part of my 110 invention. A bundle carrier so constructed will only hold a limited number of sheaves

and if more are put on it one or more will be crowded over the ends of the teeth and be prematurely deposited or split, such causing irregular rows and giving trouble 5 during stooking and loading operations.

To obviate this difficulty I have provided the following parts as an attachment for the bundle carrier.

The outer ends or tips of a number of 10 selected teeth are vertically slotted as shown at 13 to receive a sheaf retainer 14, the retainer being in the nature of a flat bar pivotally fastened by a pivot pin 15 to the teeth so that there is a long end extending upwardly and a short end extending downwardly.

Each retainer is controlled by a controlling rod 16 slidably attached by suitable clips 17 to the underside of the selected 20 teeth 4. These rods pass inwardly towards the binder and have their outer ends connected by pairs of links 18 to the lower ends of the retainers 14 and their inner ends terminating in heads 19.

25 The heads of the rods are adapted to engage with a horizontally disposed controlling guide bar 20 permanently secured to the lower ends of a pair of end hangers 21 and 22 attached to the end brackets. 30 This bar is for the greater part straight but is provided in a proper location with bowed parts 23 and 24, the curvature of which is determined by the movement of the teeth.

35 In the normal outstanding position of the teeth the sheaf retainers 14 take an upright position as shown in the drawing, the upper ends being locked against outward swing by the heads 19 of the controlling rods being 40 engaged with the straight part of the bar 20.

Consequently the retainers positively prevent the sheaves from escaping prematurely over the ends of the teeth and being scattered on the ground and also allow of more 45 sheaves being deposited on the carrier than is customary.

In the movement of the teeth as effected 50 through the turning of the rod 8 the controlling rods are caused to swing with the teeth and to follow the movement thereof with the result that when the outer ends of the bundle carrier teeth drop the inner ends of the controlling rods ride and escape 55 from the controlling rod guide bar. The controlling rods are consequently then free to shift endwise towards the binder and the instant they are free the upper ends of the retainers swing out to approximately 60 a horizontal position as it is to be remembered that the sheaves carried by the bundle carrier have a constant outward pressing action on the retainers which sets them in motion the instant the heads 19 are free.

65 After the heads of the controlling rods

free the guide bars they continue moving with the teeth and actually swing forwardly. The movement just described allows the retainers to unlock and drop down and free the sheaves and take approximately a horizontal position when the bundle carrier has reached its dropped rear position as shown in dotted outline Figure 2.

In the return movement of the bundle carrier teeth which is brought about by turning the rod 8 in the reverse direction, the initial movement is the raising of the outer ends of the teeth, which movement lowers the heads of the controlling rods into the plane of the controlling rod guide bar. The further movement of the teeth on the return, 75 swings the control rods in the direction indicated by the dotted line 25 (Figure 2) where they are brought to the curved part of the bar and in travelling this curved part 80 are gradually shoved endwise outwardly with the result that when the teeth have reached the original loading position the control rods have been pushed outwardly to their full extent and the retainers have been 85 again brought to their original upright position in which they are locked against outward swing.

I have shown the retainers as mounted on two teeth but it will be readily understood 90 that the number could be increased as desired provided guide rods are supplied to control them.

What I claim as my invention is:—

1. In a bundle carrier, the combination 100 with sheaf receiving and bundle forming teeth and means for operating the teeth to discharge the bundle and return to the original sheaf filling position, of sheaf retainers located at the outer ends of selected bundle 105 carrier teeth and means for controlling the retainers automatically operating to hold them in a fixed position in the sheaf filling position of the carrier teeth, to release them in the discharging movement of the carrier 110 teeth and to reset them in the initial position upon the carrier teeth returning to the original sheaf receiving position.

2. In a bundle carrier, the combination 115 with sheaf receiving and bundle forming teeth and means for operating the teeth to discharge the bundle and return to the original sheaf filling position, of a plurality of sheaf retainers carried by selected teeth and located at the outer ends of the teeth, means 120 for locking the retainers in an upright position against the outward pressure of the sheaves and means for releasing and returning the sheaf retainers to comply with the discharge and return movement of the teeth. 125

3. In a bundle carrier, the combination 130 with sheaf receiving and bundle forming teeth and means for operating the teeth to discharge the bundle and return to the original sheaf filling position, of a plurality of

normally upstanding sheaf retainers located at the outer ends of selected teeth, endwise movable controlling rods carried by the teeth and connected to the retainers and a permanently mounted guide bar engageable with and controlling the movement of the rods and designed to lock the rods against end movement inwardly in the sheaf receiving position of the teeth and thereby prevent the outward swinging of the upper ends of the retainers and in the discharging and resetting movement of the teeth to release the rods in the discharge movement and to reset

them in the initial locked position on the return movement.

4. An arrangement according to claim 3, in which the permanently mounted guide bar is provided with an irregular bearing surface engageable with the endwise movable controlling rods.

Signed at Shoal Lake, this 18th day of February, 1920.

NEIL MACLEAN CAMERON.

In the presence of:—

ISABELLA DICKINSON,
M. C. MARKLE.
